DESIGN FOR A CONTROL DESK

Max J. Rubel, Pittsburgh, Pa., assignor to Westinghouse Electric & Manufacturing Company, a corporation of Pennsylvania

Application August 11, 1939, Serial No. 86,603

Term of patent 7 years

To all whom it may concern:

Be it known that I, Max J. Rubel, a citizen of the United States, residing at Pittsburgh, in the county of Allegheny and State of Pennsylvania, have invented a new, original, and ornamental Design for Control Desks, of which the following is a specification, reference being had to the accompanying drawing, constituting a part thereof.

The figure is a view, in perspective, of a control desk, showing my new design.

The dominant features of my design reside in the superstructure.

I claim:

The ornamental design for a control desk, substantially as shown and described.

MAX J. RUBEL.
